UNITED STATES PATENT OFFICE.

CHRISTIAN J. BOOS, OF JACKSON, MICHIGAN.

BRICK-MAKING MACHINE.

No. 831,596.

Specification of Letters Patent.

Patented Sept. 25, 1906.

Application filed December 7, 1905. Serial No. 290,795.

To all whom it may concern:

Be it known that I, CHRISTIAN J. BOOS, a citizen of the United States, residing at Jackson, in the county of Jackson and State of Michigan, have invented certain new and useful Improvements in Brick-Making Machines, of which the following is a specification.

This invention relates to brick-making machines.

One object of the invention is to provide a brick-machine provided with a swinging mold having means designed to hold the finished bricks against accidental displacement with respect to the pallet-board when the mold is shifted from over the bricks and pallet-board.

Another object is to provide a brick-machine having a face-plate designed to hold the bricks against accidental displacement when the mold is shifted out of contact with the completed bricks.

Another object resides in the provision of a brick-machine embodying such characteristics that its mold may be readily shifted forwardly and backwardly upon a horizontal axis.

Another object is to provide a comparatively simple, inexpensive, durable, and efficient machine of the nature stated.

Another object is to provide a machine of the nature stated embodying such characteristics that the mold may be readily and properly positioned to receive the plastic material and then swung to an inverted position to permit of the ready discharge of the molded material.

A still further object resides in the provision of a brick-machine so constructed and arranged that the mold thereof may be readily and quickly dropped from one position to another and then turned over into an inverted position to permit of the ready removal of the bricks therefrom.

It is still further designed to provide a brick-machine embodying such characteristics that the mold may be dropped in a vertical direction from one position to another and then turned over vertically to an inverted position, there being a face-plate so constructed and arranged with respect to the mold and the bricks to hold the latter against accidental displacement relative to the pallet-board when the mold is given a reverse turn from over the bricks to be positioned for repetition of the aforesaid movements.

With the above and other objects in view the present invention consists in the combination and arrangement of parts hereinafter described, shown in the accompanying drawings, and particularly pointed out in the appended claims, it being understood that changes may be made in the shape, size, proportions, and minor details within the scope of the claims without departing from the spirit or sacrificing any of the advantages of the invention.

In the drawings, Figure 1 is a perspective view of the machine ready for operation. Fig. 2 is a similar view illustrating the mold dropped from its normal position to an inclined plane. Fig. 3 is another similar view illustrating the mold in its inverted position. Fig. 4 is a similar view of the mold when moved from over the bricks to permit the removal of the pressed or molded bricks. Fig. 5 is a transverse sectional view on the line *a a* of Fig. 1, illustrating the inverted position of the mold in dotted lines. Fig. 6 is a transverse sectional view on the line *b b* of Fig. 4. Fig. 7 is a detail view of one of the clamping-elements. Fig. 8 is a detail view of the other clamping element.

In carrying out the present invention the mold of the machine is indicated by the numeral 1 and is mounted for operation within a suitable frame consisting of ground-sills 2 and 3, upon which are secured in any suitable manner the pairs of supporting-legs 4 and 5, respectively, the front legs of each pair being connected intermediate their ends by a cross-piece 6, upon which latter and connecting the respective pairs of supporting-legs are suitable arms 7 and 8. It will thus be seen that since the cross-piece 6 is disposed at a right angle to the arms 7 and 8 and the latter resting upon the former the arms thereby and by their connection with the supporting-legs are firmly supported for the purpose for which they are designed and as will be apparent from a further reading of this specification. The supporting-legs above the arms 10 are connected by the side members 9 and 10 and the back member 11, between which and intermediate the upper and lower edges thereof is arranged a shelf 12 designed for the reception and support of the brick-making material, all of which is clearly shown in the accompanying drawings.

Side rails 13 and 14 are connected to the in-

ner faces of the respective arms 7 and 8 and have their upper faces extending slightly above the upper faces of the arms, each being provided in its upper face with a forward and 5 a rearward socket, as indicated by the characters 15 and 16, the respective sockets of the opposite arms being in alinement. Each rail 13 and 14 is provided with a depending perforated ear 17, which are designed to 10 aline and in which is journaled a horizontally-disposed shaft 18, arranged beneath the plane of the under faces of the aforesaid arms 7 and 8. Mounted upon and for rotation with this said shaft 18 are two clamping-levers 19, provided each with an ear 19', 15 adapted to coöperate with the lugs 20, one of the latter being disposed upon the adjacent ear 17 of the rails 13 and 14 for a purpose presently understood. A screw or other 20 suitable element 19^a is passed through each lug 20 for coöperation with the corresponding ear 19'.

The mold in the present instance comprises sides 21 and 22, each provided with an ear 24. 25 Each side is also provided with a slot 25, adjacent each of which latter is arranged a pair of ears 26, designed to receive pivotally between them a cam or other lever 27, designed to enter through the corresponding slot 25 30 and secure the pallet-board 28 in proper position against accidental displacement with respect to the mold-box. The back of the mold-box is in the form of a facing-plate 29, provided with a series of vertical slots 30 for 35 the reception therein of the division-plates 31 of the mold. The upper edge of the back plate 29 is directed outwardly from the mold for engagement with the aforesaid bench or shelf 12 to prevent it from swinging outwardly 40 upon its pivot-rod 32, the latter being disposed in the alining ears 24 of the respective sides of the mold. The front of the mold is formed by the separators or boxes 33, between which the corresponding ends of the 45 corresponding division members or plates 31 are fitted, there being suitable bolts 34 and 35 passed through the sides 21 and 22, the separators 33, and also the division-plates 31. The bottom of the mold is strengthened by 50 means of a metal or other suitable strip 36, as shown.

While the back plate of the mold serves as a facing-plate, the inner faces of the aforesaid boxes or separators do not form the 55 front facing members. On the other hand, I provide a swinging arm 37, which is preferably of an inverted-T formation in section and whose base portion 38 is secured, by means of a series of suitable fastenings 39, to 60 the flanged edge 40 of a series of combined front and bottom facing members and means for holding the bricks against displacement with respect to the aforesaid pallet-board. These combined members are of a Z form, as 65 shown, the portions 41 being secured to the

aforesaid arm 37, the portions 42 serving as the front facing members and the portions 43 serving as the bottom facing members, the free ends of the latter resting upon cleats or shoulders 44 when lowered into the mold. 70 The first-named portions of the Z-shaped members are out of contact with the spacing separators or boxes, as clearly shown in Fig. 5. The arm 37 is provided with appropriate slots 45 on its front portion to prevent interference with the tops of the division-plates during revolution of the mold. This arm 37 also has a finger 47 at each end for a purpose presently explained.

Connecting the rails 13 and 14 is a pallet-board support 48, provided with the adjustable pallet-board connections 49, and it is between this support 48 and the shelf 12 that the mold is positioned. For instance, each side member 21 and 22 of the mold has a 80 trunnion or fulcrum 50 for engagement in the alining rear sockets 16 of the rails 13 and 14, and these trunnions or fulcrums aid the slotted guide-plates 51 and 52 to support the mold-box in a horizontal position, the lower 90 ends of the slots of said plates terminating at an angle to the elongated portion thereof to form a shoulder 53 for engagement upon the corresponding projection 54 of the side rails 13 and 14. These guide-plates are provided 95 with trunnions or fulcrums 55 at their upper ends, which are perforated, whereby the guide-plates may have pivotal movement upon the corresponding end of the pivot-bolt 56, upon which the aforesaid swinging arm 100 37 is mounted. It will thus be understood that the shoulders of the guide-plates may be disengaged from the projections 54 of the rails 13 and 14 to permit dropping of the front end of the mold, so that the fulcrums 105 55, which are rounded, may engage in the front alining sockets 15 of said rails and dispose the mold-box upon a forward incline, as shown in Fig. 2.

The operation of my invention is as follows: 110 Regardless of the character of frame in which the mold is mounted, it will be stated that the concrete or plastic substance is placed in the mold when the same is in the position shown in Fig. 1. As illustrated, the 115 shelf 12 prevents outward movement of the back facing-plate and is arranged, preferably, upon a level with the upper edge of the back facing-plate. The material is taken from said shelf and placed within the mold, after 120 which and while the mold is in the position shown in Fig. 1 the pallet-board 28 is placed in proper position and clamped by means of the clamping elements 27. The guide-plates 125 51 and 52 are swung slightly, causing their shoulders to become disengaged from the projections 54 of the rails 13 and 14 when the box falls to the position shown in Fig. 2. In this position the trunnions or fulcrums 55 are disposed in the forward alining sockets 130 135

of the rails 13 and 14. The mold-box is then revolved or swung upon bolt 56 into the position shown in Fig. 3, the ends of the fingers 47 of the swinging arm 37 being clamped between the lugs 20 of the depending ears of the side rails 13 and 14 and the ears of the clamping-levers. The levers for holding the pallet-board are then manipulated to permit of the loosening of the latter. A lever *b* is then inserted in the socket *c* of the back plate, and the lever 19 is raised until the fingers 47 of the arm 37 are held firmly against the lugs on the inner faces of the depending ears of the rails 13 and 14, and then the mold-box, with the exception of the pallet-board and the series of combined double face-plates and brick-holding elements, is rotated or swung backwardly, as shown in Fig. 4. It will thus be seen that the pallet-board, with the finished bricks thereupon, is left upon the pallet-board support and that as the mold-box is moved backwardly to leave the pallet-board and bricks in the position stated the double facing members serve to prevent displacement of the bricks with respect to the mold-box. After this operation downward pressure upon the lever 19 will cause the double facing members to move away from the bricks to a slight degree, so that the pallet-board and bricks may be removed from the pallet-board support. Then the double facing members and brick-holding means may be rotated or shifted backward upon the pivot 56 until it is possible to lift it and the mold-box to a horizontal position for repetition of the operations described. It might be remarked that the arms *a* of the fulcrums 55 may be used to disengage the guide-plates 51 from the projections 54 and also to swing the mold.

From the foregoing it will be seen that the mold-box may be dropped vertically upon a forward incline and then turned completely over into inverted position. It will also be seen that the mold may be turned from over the bricks with elements of the same, serving to prevent accidental displacement of the bricks with respect to the pallet-board support or the pallet-board itself and afterward moved into engagement for coöperation with the mold-box. In other words, it will be seen that when the mold-box has been thrown to its inverted position parts thereof may be taken from over the bricks, while a part or parts remain adjacent the bricks to prevent accidental dislodgment of the latter. It will also be understood that when the lever *b* is used to throw the mold back the operation causes a slight swinging of the back plate to prompt the latter to clear the corresponding faces and edges of the bricks, thereby preventing chipping or breaking of the latter.

What is claimed is—

1. A brick-making machine, comprising a

mold constructed and arranged for a vertical, intermittent, swinging movement into inverted position and means to prevent accidental displacement of the contents of the mold when discharged therefrom.

70

2. A brick-making machine, comprising a mold constructed and arranged for vertical swinging movement and means to prevent accidental displacement of the contents of the mold when discharged therefrom.

75

3. A brick-making machine, comprising a mold constructed and arranged for vertical backward and forward movement and means to prevent accidental displacement of the contents of the mold when discharged therefrom.

80

4. A brick-making machine, comprising a frame, a mold mounted for swinging movement within the frame, a double facing member associated with the mold, and means constructed and arranged to present the double facing member with respect to the completed bricks to prevent accidental displacement of the latter when the mold is swung from over the bricks.

85

5. A brick-making machine, comprising a mold composed of separable parts, means constructed and arranged whereby the mold may be swung upon a horizontal axis and means to prevent accidental displacement of the contents of the mold when discharged therefrom.

95

6. A brick-machine comprising a frame, a mold mounted for swinging movement within the frame, the mold including a double facing member, and means constructed and arranged whereby the double facing member may be separated from the mold when the latter is swung from over the completed bricks.

105

7. A brick-making machine, comprising a frame, a pallet-board support mounted upon the frame, a mold having each side provided with a slot, a pallet-board for disposition upon the top of the mold, a lever mounted for projection through each of said slots to detachably secure the pallet-board against displacement, means constructed and arranged whereby the mold may be swung vertically to inverted position upon the pallet-board support to permit of the removal of the completed bricks from the mold and means carried by the mold to prevent accidental displacement of the bricks from the pallet-board when the bricks are discharged from the mold.

110

115

120

8. A brick-making machine comprising a swinging mold, a pallet-board detachably associated with the mold, and a double facing member mounted for swinging movement with the mold, and also independently thereof.

125

9. A brick-making machine, comprising a swinging mold, a pallet-board detachably mounted upon the mold, and a series of double facing members mounted for swinging

130

- movement with the mold and also independently thereof.
10. A brick-making machine comprising a swinging mold, and a double facing member mounted for swinging movement with the said mold and also independently thereof.
11. A brick-making machine, including a swinging mold, and a series of double-facing members mounted for swinging movement with the mold and also independently thereof.
12. A brick-making machine, comprising a mold having each side provided with a slot and a pair of ears adjacent each slot, a pallet-board, a lever pivotally mounted in each pair of said ears for projection through the corresponding slot to detachably secure the pallet-board in place and means to prevent accidental displacement of the bricks when discharged from the mold.
13. A mold of the class described, including division-plates, a hinged back-facing plate, a series of combined front and bottom facing plates, and a removable pallet-board.
14. In a device of the class described, a mold, including division-plates, a hinged back plate, a combined front and bottom facing member, and a removable pallet-board.
15. A brick-making machine, comprising a swinging mold, means whereby the mold may be turned to an inverted position, and double facing members associated with the mold to prevent accidental displacement of the bricks when the mold is swung from over the bricks.
16. A brick-making machine, comprising a swinging mold composed of separable parts, and means constructed and arranged whereby the mold may be swung to an inverted position, parts of the mold preventing displacement of the bricks when the mold is swung backwardly from over the bricks.
17. A brick-machine, comprising a swinging mold including separable facing-plates, two of the facing-plates being formed of a single piece of material, means for swinging the mold into an inverted position, and means constructed and arranged whereby the double facing-plates may prevent displacement of the bricks when the mold is swung backwardly.
18. A brick-making machine, comprising a swinging mold composed of separable facing members, means whereby the mold may be swung to an inverted position, and means whereby some of the facing members will prevent accidental displacement of the bricks when the mold is swung from over the bricks, the latter facing members being each formed of a single piece of material of substantially Z shape.
19. A brick-making machine comprising a swinging mold composed of separable parts, and means constructed and arranged whereby a part of the mold may be separated from other parts thereof when the mold is swung
- from over the bricks to prevent accidental displacement of the latter when discharged from the mold.
20. A brick-making machine comprising a swinging mold composed of separable facing members, a part of the mold preventing accidental displacement of the bricks when discharged from the mold.
21. A brick-making machine comprising a mold constructed and arranged for vertical swinging movement, and means to prevent accidental displacement of the bricks when discharged from the mold.
22. A brick-making machine comprising a mold constructed and arranged for vertical swinging movement into inverted position, a part of the mold preventing accidental displacement of the bricks when the mold is swung to its normal position.
23. A brick-making machine, including a combined tilting and swinging mold and means to prevent accidental displacement of the contents of the mold when discharged therefrom.
24. A brick-making machine, including a combined vertically tilting and swinging mold and means to prevent accidental displacement of the contents of the mold when discharged therefrom.
25. A brick-making machine, including a combined tilting and swinging mold composed of separable parts and means to prevent accidental displacement of the contents of the mold when discharged therefrom.
26. A brick-making machine comprising a combined tilting and swinging mold including means to prevent accidental displacement of the bricks when discharged from the mold.
27. A brick-making machine comprising a mold movable about two separate and independent axes and means to prevent accidental displacement of the contents of the mold when discharged therefrom.
28. A brick-making machine comprising a mold movable about two separate axes and means to prevent accidental displacement of the contents of the mold when discharged therefrom.
29. A brick-making machine comprising a mold movable about two separate axes and including means to prevent accidental displacement of the bricks when discharged from the mold.
30. A brick-making machine including a combined tilting and swinging mold, both movements thereof being in the same direction and means to prevent accidental displacement of the contents of the mold when discharged therefrom.
31. A brick-making machine including a mold provided with a shiftable fulcrum element and means to prevent accidental displacement of the contents of the mold when discharged therefrom.

32. A brick-making machine including a mold provided upon opposite parts with diagonally opposite fulcrum members and means to prevent accidental displacement of the contents of the mold when discharged therefrom.

33. A brick-making machine including a mold provided upon opposite parts with diagonally opposite fulcrum members, a support provided with bearing-notches for coöperation with said fulcrums and means to prevent accidental displacement of the contents of the mold when discharged therefrom.

34. A brick-making machine including a mold provided with fulcrum members, a support provided with bearing-notches for coöperation with said fulcrum members and means to prevent accidental displacement of the contents of the mold when discharged therefrom.

35. A brick-making machine including a swinging mold provided with separable facing members, one of said facing members being arranged to swing with the mold and also independently thereof to prevent accidental displacement of the bricks discharged from the mold.

36. A brick-making machine including a swinging mold having one element thereof movable independently of the mold during movement of the latter to prevent accidental displacement of the bricks discharged from the mold.

In testimony whereof I affix my signature in presence of the subscribing witnesses.

CHRISTIAN J. BOOS.
